INVENTOR,

Joseph D. Axtell

UNITED STATES PATENT OFFICE.

JOSEPH D. AXTELL, OF SANTA BARBARA, CALIFORNIA.

SASH FASTENER AND HOLDER COMBINED.

SPECIFICATION forming part of Letters Patent No. 378,351, dated February 21, 1888.

Application filed October 14, 1887. Serial No. 252,315. (No model.)

To all whom it may concern:

Be it known that I, JOSEPH D. AXTELL, a citizen of the United States of America, residing at Santa Barbara, in the county of Santa Barbara and State of California, have invented 5 certain new and useful Improvements in Sash-Fasteners; and I do hereby declare the following to be a full, clear, and exact description of the invention, such as will enable others skilled 10 in the art to which it appertains to make and use the same, reference being had to the accompanying drawing, and to letters or figures of reference marked thereon, which form a part of this specification.

15 My invention has reference to sash-fasteners; and it consists in the novel combination and arrangement of the parts thereof, which will be more fully hereinafter described, and particularly pointed out in the claim.

20 The primary object of my invention is to provide a sash-fastener which is adapted to have either a frictional or positive engagement with the casing, or the use of both securements, if so desired, thereby providing a fastener which 25 is especially adapted for use with car-windows.

The secondary object of my invention is to arrange the parts of the device in a simple and accessible manner, and so combine the same that they shall be strong and durable, readily 30 applied, and easily operated.

I attain these objects by the device illustrated in the accompanying drawing, wherein a sectional elevation of my improvement is shown in connection with a sash and casing, letters of 35 reference being used to designate the parts.

A indicates the casing, and B the sash. A rectangular plate, C, is secured to the sash adjacent to the casing by means of screws s , passing through the apertured ends of the said 40 plate. About midway of the inner edge of the plate C an integral ear, C', is formed, which has an aperture formed near its inner edge.

Over the plate C a plate, D, having angularly-bent ends is secured, and with said plate 45 C forms a rectangular box or casing. The inner central edge of the plate D is also formed with an integral apertured ear, D', similar in form to the ear C', and mounted directly over the same. Within the casing formed by the 50 plates C and D an extended rectangular rubber block, E, is mounted, and between the ears d' and e' a cam-disk, F, is eccentrically se-

cured by a pivot-pin, f, passing through the said ears and through the cam-disk. Integrally formed with the said cam-disk is an operating-handle, F', which is formed with an angular extension, F², having an operating finger-ring, F³, formed therewith.

To the top portion of the casing formed by the plates D and C a plate, G, is secured, which is constructed with upwardly-projecting end ears, g g, having apertures therein through which a bolt, H, passes and has movement. This bolt has an angularly-disposed finger-piece, h, secured thereto, and over said bolt H, between the said finger-piece and the one ear g, a coiled spring, S, is mounted, which has the tendency to impel the bolt into apertures formed in the casing. An ear, d', is formed with the outer plate, D, which projects upward in front of the opening between the ears g g of the bolt-plate G. The hand-piece h may be pressed down and bear against either side of the said ear, and thereby retain the bolt H in an open or closed position, as will 75 be readily understood.

The operation of my improvement is simple and of a twofold nature. When it is desired to use a rubber frictional fastening, the sash is raised the desired height and the handle carrying the cam-disk F is drawn outward, as shown in dotted lines, and the said disk thereby forced against the rubber block E, which in turn presses against the casing and securely retains the sash against movement.

85 The casing will be provided with suitable apertures for the reception of the end of bolt H, said apertures being arranged at certain regulated distances apart. It will thus be seen that the said bolt may be used independently 90 of the frictional rubber block E.

Occasion may require the window or sash to be raised to such a distance where there is no aperture for the bolt H to engage with. In that event the frictional fastening will be used 95 alone, and its convenience and utility be readily apparent.

The important advantage of my improvement consists in the double form of fastening, which may be individually or unitedly used, too and if one or the other should become deranged or broken there would still be a fastening intact with the sash.

Though my improvement is especially adapt-

ed for use in car-windows, it may be used in connection with any form of window-sash with equal facility. The parts are all firmly secured, positive in their desired result, and 5 convenient for operation, and an attachment is formed which combines the double construction of a bolt and the advantage of a frictional fastener.

Having thus described my invention, what 10 I claim as new, and desire to secure by Letters Patent, is—

The combination, with the plates D and C, having the ear d' , and inclosing the rubber

frictional contact-fastening, and the cam F, for operating the same, of the plate G, having 15 end apertured ears, g , the bolt H, having the finger-piece h , adapted to engage with either side of said ear d' , and the coiled spring S, substantially as described.

In testimony whereof I affix my signature in 20 presence of two witnesses.

JOSEPH D. AXTELL.
